ELECTRICAL DISTRIBUTION SYSTEM.

Application filed January 25, 1927, Serial No. 163,511, and in Switzerland January 30, 1926.

My invention relates to electrical distribution systems and it has particular relation to an arrangement for controlling the voltage of two alternating-current systems which are 5 interconnected by means of a transformer.

Among the objects of the invention is the provision of a system of the above character provided with means for adjusting the voltage of one system independently of that of 10 the other system without requiring complicated tap-changing apparatus, switching arrangements, or other complicated mechanisms, such as used heretofore.

According to the invention the voltage on 15 one side of a transformer is controlled independently of that of the other side of the transformer by providing an independent control of the excitation of the transformer core. The transformer is arranged so as to 20 include a relatively large reactance in the connections to the network with respect to which it is to be independent, and any voltage difference between the networks that are to be interconnected by the transformer is taken 25 care of by the voltage drop in the series reactance, said voltage drop being determined by the amount of excitation supplied to the transformer through the independent excitation control.

30 The foregoing and other objects of the invention will be best understood from the accompanying drawings in which:

Fig. 1 is a diagrammatic illustration of a 35 distribution system embodying the invention;

Fig. 2 is a diagram similar to Fig. 1 illustrating another form of the invention; and

Fig. 3 is an explanatory vector diagram referred to hereinafter.

In general, it is not possible to regulate 40 or independently adjust the primary and secondary voltages of a transformer, or the transformer ratio, without in some way decreasing or increasing the number of effective turns of the windings. The voltage ratio is 45 fixed by the ratio of the turns. The only way which seemed heretofore practicable for varying the ratio consisted in adjusting the relative number of the turns in the primary and secondary windings of the transformer.

50 Such system of regulation has serious disadvantages. It requires regulating switches and switching contacts; a particular type of winding distribution on the transformer with special taps and lead connections; and above

all, it requires special arrangements for permitting carrying out the switching operations while the transformer windings are carrying current, so as to prevent short-circuiting of the transformer, and at the same time avoid interruption of the current flow therethrough. These special switching arrangements are not only very expensive, but are, in addition, complicated and subject to damage and are accordingly very undesirable.

According to the invention a much more 55 satisfactory system of regulation of the voltage ratio is obtained by controlling the excitation of the transformer, and thereby varying the voltage drop between the transformer and the network with respect to which it is 60 to be independent. To this end, the transformer may be provided with a large leakage and a variable voltage component may be injected between the two systems by means of a synchronous condenser which is connected 65 to the transformer so as to vary the excitation thereof. The synchronous condenser is so connected to the transformer as to maintain the voltage on one side thereof as desired, and absorb the voltage difference between the 70 transformer and the other side thereof in the leakage reactance of the transformer with respect to said other side. Thus, for instance, the synchronous condenser may be directly connected to the side of the transformer, the 75 voltage of which is to be regulated. If the voltage on the other side of the transformer is fixed and should be left undisturbed, the voltage of the system that is to be regulated will be determined by the excitation of the 80 synchronous condenser. The difference between the voltages of the two systems is then absorbed in the leakage reactance of the transformer interconnecting the two systems. In such arrangements the leakage-reactance 85 voltage drop may assume considerable value and the vector diagram of the voltages must then conform to the requirement that not two, but three voltage components shall give a resultant equal to zero.

100 An arrangement of such character utilizing a synchronous condenser connected to one side of a transformer for independent regulation of the voltage on one side of the transformer from that of the other side, and depending on the large leakage reactance between the two transformer halves for this regulation, is shown in Fig. 1. An alternat-

ing-current network system I is shown connected to an alternating-current network system II through a transformer T, having a primary winding 1 and a secondary winding 2 connected to the two systems, respectively. Let us assume that the alternating-current system I is a part of a large network that is to be maintained at a fixed voltage, and that the voltage of this network shall remain fixed, and that the alternating-current system II shall be regulated independently of the first-mentioned system.

In order to carry out this system of regulation in accordance with my invention, I connect a synchronous condenser 5 across the terminals of the transformer winding 2, to which the alternating-current system II is connected, and control the voltage of the condenser as desired. This control may be effected, for instance, by varying the current supplied to the exciting winding 6 of the synchronous condenser through a regulator 7 which is suitably set to secure the desired voltage control. The regulator 7 may, for instance, be arranged to be actuated in response to the voltage of the alternating-current system II, being connected to the terminals thereof. The excitation current for the exciting winding 6 of the condenser is shown derived from an exciter 8 which may be directly driven by the condenser, or arranged in any suitable manner. By varying the excitation of the field winding 6 the voltage across the terminals of the synchronous condenser 6 may be varied as desired, and thereby the voltage of the alternating-current system II adjusted. The difference of the voltage between the alternating-current systems I and II is then covered by the leakage-reactance drop in the transformer T, incident to the flow of current through the transformer.

With the foregoing system independent adjustment of the voltages in the primary and secondary windings of the transformer is obtained by employing a transformer having a large effective leakage flux and an adjustable synchronous condenser connected to the side of the transformer the voltage of which is to be regulated.

In many cases the transformer voltage which is to be regulated exceeds considerably the voltage for which synchronous condensers, or in general, rotating dynamo-electric machines may be economically or conveniently built. Accordingly, in many cases it is desirable to use a three-winding transformer in which one of the windings has a much larger leakage reactance than the other two windings. The line, the voltage of which is to be regulated, and the synchronous condenser are then connected to the two windings with low-leakage reactance. The third winding with high-leakage reactance is connected to the other line which is to be unaffected by the voltage regulation of the first-mentioned line.

An arrangement of such character is shown in Fig. 2, in which the transformer T interconnecting the primary network I with the secondary network II has, in addition to the primary and secondary windings 1 and 2, respectively, a tertiary winding 3 having its terminals connected to a synchronous condenser 5. The synchronous condenser has an exciting winding 6 which is supplied from an exciter 8, the voltage of which is controlled by a regulator 10 to carry out any desired type of regulation of the voltage of the network II. In order to make the voltage of the secondary network II independent of that of the primary network, the transformer T is so arranged that there is a relatively large-leakage reactance between the primary and secondary windings 1 and 2, and a relatively low-leakage reactance between the secondary and the tertiary windings 2 and 3. On account of the close coupling of the tertiary winding 3 with the secondary winding 2, the voltage of the synchronous machine 5 will determine the secondary voltage of the transformer across the secondary network II, and this voltage may be readily varied by changing the excitation of the synchronous machine. The difference of the voltage between the primary and secondary network is then covered by the voltage drop in the leakage reactance between the transformer windings 1 and 2 incident to the flow of current from the primary network I through the transformer.

The voltage of the synchronous condenser, and therethrough the voltage of the secondary network 2, may be regulated to suit any particular operating requirements that may occur in practice. For instance, it is sometimes desired to vary the voltage of a high-voltage transmission line independently of the voltage of the power station from which it is being supplied. In other cases, it may be desirable to limit in a predetermined manner, the flow of power in a tie line interconnecting two power stations, or two independently supplied networks. In the latter case, an arrangement of the foregoing character permits the control of the phase and magnitude of the voltage in the tie line so as to secure the most favorable conditions with a minimum loss. In still other cases, it may be desirable to so control the voltage of the secondary network as to definitely limit the amount of power derived from the primary network and prevent the power derived therefrom through the transformer from exceeding a predetermined value. In all such cases the regulator may be arranged to be automatically controlled in response to some electric quantity of the system in order to carry out the desired regulation.

The system shown in Fig. 2 illustrates, by way of example, the method of regulation arranged to so control the voltage of the second-

ary network II as to prevent the load from the primary network I from exceeding a predetermined value. To this end the regulator 10 is actuated in response to the combined effect of the voltage across the primary network I, and the current flowing in said network to the transformer T, the voltage coil 11 of the regulator 10 being connected across the primary network and the current coil 12 of the regulator to a current transformer 13. Fig. 3 gives a vector diagram illustrating an approximation of conditions of the power exchange between the networks I and II when a regulating system, such as shown in Fig. 2, is employed.

Assuming that $OA = e_1$ is the voltage of the primary network I and that the effective power-transmitted to the network II shall remain constant, then the line $m-m$, perpendicular to the vector e_1 , is the locus of the ends of the vectors $i_1, i_1', i_1'' \dots$ representing the current flowing from the network I into the transformer T. For the case corresponding to the flow of current represented by the vector i_1 in phase with the primary voltage e_1 , there will be an inductive drop in the leakage reactance between the primary coil 1 and the secondary coil 2 of the transformer corresponding to the vector A B, perpendicular to the voltage vector e_1 . The vector $OB = e_2$ will then represent the voltage e_2 across the secondary winding of the transformer. The voltage across the terminals of the synchronous condenser will then be of substantially the same phase as secondary voltage e_2 corresponding to the vector $OC = e_3$. Since the leakage between the primary and secondary windings 1 and 2 is much larger than that between the secondary and tertiary windings 2 and 3, the vector $BC = e_3 - e_2$ will be much smaller than the vector A B corresponding to the leakage drop between the primary and secondary windings. Corresponding to the different changes in the operating conditions, the excitation of the synchronous condenser 5 is controlled by the regulator 10 so as to cause the primary-current vectors i_1 , etc., to move along the line $m-m$. The end of the vector e_1 , corresponding to the voltage across the synchronous condenser, will then move on a line $o-o$ perpendicular to the line $m-m$, and the voltage vector e_2 , corresponding to the voltage across the secondary winding 2 of the transformer, will move along a line $n-n$ parallel to $o-o$. Thus, for the case of current i_1' , the condenser voltage is represented by the vector e_2' , and the voltage across the secondary transformer winding by the vector e_2'' . In every case the vectors A B' and A B'', etc., representing a voltage drop in the leakage reactance between the primary and secondary windings of the transformer, will be perpendicular to the current vectors i_1', i_1'' , etc.

The system of regulation described hereinabove makes it possible to control the voltage

on one side of a transformer independently of that of the other side of the transformer, without complicated and expensive switching or regulating devices. The new regulating system depends essentially on the fact that by varying the excitation of a synchronous alternating-current machine, such as a synchronous condenser, it is possible to control the voltage across one side of the transformer independently of that of the other side, the difference in voltage between the two transformer windings being absorbed by the drop in the leakage reactance embodied in the transformer, or in the connections thereto.

I claim:

1. In an electrical distribution system comprising a primary network and a secondary network and a transformer interconnecting said networks, said transformer having a fixed ratio of the primary winding to the secondary winding, means for controlling the voltage across one winding of the transformer without varying the voltage across the other winding thereof comprising a synchronous condenser connected to the winding of the transformer, the voltage of which is to be regulated, said transformer embodying sufficient reactance to absorb the voltage drop corresponding to the desired regulating range.

2. An electrical distribution system comprising a transformer having primary and secondary windings, primary and secondary alternating-current lines connected thereto, respectively, and means for controlling the voltage on one winding of the transformer independently of that of the other winding thereof while maintaining substantially the same ratio of the turns of the primary and secondary windings, said means comprising condenser means connected to the winding of the transformer the voltage of which is to be regulated.

3. An arrangement according to claim 2, comprising a transformer having a tertiary winding connected to the synchronous condenser.

4. An electrical distribution system comprising a primary network, a secondary network, a transformer comprising primary and secondary windings connected to said networks, respectively, said windings comprising relatively large reactance, and means for controlling the voltage on one winding of the transformer independently of that of the other winding without substantially varying the ratio of the turns of the primary and secondary windings, said means comprising a tertiary winding having relatively close coupling with the transformer winding whose winding is to be independently controlled, a synchronous machine connected to said tertiary winding, and means for varying the excitation of said synchronous machine.

5. An electrical distribution system com-

- prising a primary network, a secondary network, a transformer comprising primary and secondary windings connected to said networks, respectively, said windings comprising relatively large reactance, means for controlling the voltage on one winding of the transformer independently of that of the other winding without substantially varying the ratio of the turns of the primary and secondary windings, said means comprising a tertiary winding having relatively close coupling with the transformer winding whose winding is to be independently controlled, a synchronous machine connected to said tertiary winding, and means for varying the excitation of said synchronous machine in response to the electrical conditions in one of said networks. 30
5. An electrical distribution system comprising a primary network, a secondary network, a transformer comprising primary and secondary windings connected to said networks, respectively, said windings comprising relatively large reactance, means for controlling the voltage on one winding of the transformer independently of that of the other winding without substantially varying the ratio of the turns of the primary and secondary windings, said means comprising a 35
- 10 tertiary winding having relatively close coupling with the transformer winding whose winding is to be independently controlled, and condenser means connected to said tertiary winding.
6. An electrical distribution system comprising a primary network, a secondary network, a transformer comprising primary and secondary windings connected to said networks, respectively, said windings comprising relatively large reactance, means for controlling the voltage on one winding of the transformer independently of that of the other winding without substantially varying the ratio of the turns of the primary and secondary windings, said means comprising a 40
- 15 tertiary winding having relatively close coupling with the transformer winding whose winding is to be independently controlled, a synchronous machine connected to said tertiary winding, and means for varying the excitation of said synchronous machine. 45
- 20
- 25

tertiary winding having relatively close coupling with the transformer winding whose winding is to be independently controlled, a synchronous machine connected to said tertiary winding, and means for varying the excitation of said synchronous machine in response to the electrical conditions in one of said networks. 30

7. An alternating-current-distribution system comprising a primary network, a secondary network, a transformer having primary and secondary windings connected to said network respectively, means for controlling the voltage of one winding of said transformer independently of that of the other winding without varying the ratio of the turns of the primary and secondary windings, said means comprising a synchronous machine associated with the winding of the transformer to be regulated, and means for varying the excitation of said machine. 35

In testimony whereof I have hereunto signed my name at Zurich, Switzerland, on this the 11 day of January, A. D. 1927.

FRITZ GRIEB.
